UNITED STATES PATENT OFFICE.

DAVID I. ECKERSON, OF WORCESTER, NEW YORK, ASSIGNOR OF ONE-HALF
TO JULIUS T. HADSELL AND PORTER R. HADSELL, OF SAME PLACE.

WASHING-MACHINE.

SPECIFICATION forming part of Letters Patent No. 614,710, dated November 22, 1898.

Application filed September 4, 1897. Serial No. 650,632. (No model.)

To all whom it may concern:

Be it known that I, DAVID I. ECKERSON, a citizen of the United States, residing at Worcester, in the county of Otsego and State 5 of New York, have invented certain new and useful Improvements in Washing-Machines, of which the following is a full, clear, and exact description, such as will enable those skilled in the art to which it appertains to make and 10 use the same, reference being had to the accompanying drawings, which form a part of this specification.

This invention relates to improvements in washing-machines. It has for its object the provision of a tub which is economical in the 15 use of water and at the same time gives sufficient room for the proper treatment of the goods being washed and which facilitates the passage of the goods through the machine. It 20 also has for its object the provision of a washing mechanism that can be mounted in tubs of various widths and held therein securely in its operative position or turned into the tub on which it is mounted, so as to be wholly 25 contained within the latter; and, further, it has for its object the construction of a roller mechanism that is comparatively noiseless in its operation, efficient in its purpose, and of easy operation.

30 The invention consists in the novel construction, combination, and arrangement of parts, such as will be hereinafter fully described, pointed out in the appended claims, and illustrated in the accompanying drawings.

In the accompanying drawings, in which similar letters of reference designate corresponding parts, Figure 1 is a perspective view showing the tub, the roller mechanism 40 mounted therein, and the cover for the tub. Fig. 2 is a side elevation showing the tub with its cover in place and its legs folded against its bottom. Fig. 3 is an enlarged detail view showing an end elevation of the roller mechanism, and in dotted lines shows it turned down into the tub. Fig. 3^a is a horizontal section on the line 3^a 3^a of Fig. 3. Fig. 4 is a view showing a transverse section of the roller mechanism. Fig. 5 is a side view, partly in 45 elevation and partly in section, showing the roller mechanism mounted in the tub. Fig. 50

6 is a detail view showing a plan of the under side of the base of the roller-supporting frame with one of the adjustable slides in place. Fig. 7 is a detail plan view of one of the adjustable slides. Fig. 8 is a detail view showing one of the brackets for supporting the roller mechanism in the tub.

In the drawings, A designates the tub. It consists of the sides a, the end pieces a', and the bottom a². The latter is shaped so that its ends a³ are in the form of semicylinders connected by the curved portion a⁴. By forming the bottom in this way the tub is practically divided into two parts by the inner edges 65 of the end portions and the curved portion connecting them. This formation of the tub permits an economy in the use of water and at the same time gives considerable room within which the goods can be treated. The 70 rise in the middle of the tub also serves as a guide to carry the goods away from the machine after they have passed between the rollers. The recess a⁵, formed in the under side of the bottom of the tub, allows the legs 75 supporting the tub to be turned up beneath the bottom, so that the tub can rest on the latter, and thereby occupy as little room as possible.

To the sides of the tub are attached the legs 80 B. They are pivoted to the sides by the bolts b, passing through the same near their upper ends into said sides. The legs at each end of the tub are connected by a cross-piece b'. To support the tub, the legs are turned to the position shown in Fig. 1. To hold them in their proper relative positions, cleats b² are provided. When it is desired to adjust the tub so as to occupy as little room as possible, the legs are turned up beneath the tub, with their 85 cross-pieces b' resting in the recess a⁵, formed in the under side of the bottom.

A cover C is provided whereby the tub can be turned into a table or bench, if it is so desired. The cross-pieces c serve to strengthen 90 the cover, and their dimensions are such as to fit inside the tub when the cover is in place, and thereby serve to hold the cover in place.

The washing-roller mechanism is mounted in the tub immediately over the rise or curved 95 portion a⁴ in the bottom. It is pivoted in place, so that it can be turned down into the

tub and be out of the way. It is also provided with a mechanism for locking it in its upright operative position.

The roller mechanism is secured on the base 5 D, formed with the sides d and ends d', Figs. 3, 4, and 6. Flanges d² project from the lower edges of the sides d into the interior of the base. They serve to strengthen the base and at the same time form guides for the adjustable mechanism, whereby the roller mechanism is secured in the tub.

To the under side of the base are adjustably secured the slides E, Figs. 4, 6, and 7. Each of them has projecting from its outer 15 end the lugs e. The purpose of the latter will be explained farther on. Projecting from the inner end of each slide is a lug e'. The latter extends between the flanges or guides d² of the base and has the hooks e², extending over the said flanges or guides. A slot e³ is formed in the slide and extends the length of the same. Projecting from the base D is a lug d³, provided with an aperture d⁴. A bolt d⁵ passes through the slot e³ in the slide and 20 the aperture d⁴ in the lug d³. A nut d⁶ is turned onto the projecting end of the bolt d⁵. By means of the hooks e² engaging with the flanges d² the slide can be adjusted relatively to the base and secured thereto by the bolt d⁵. 25 30 By means of these slides the roller mechanism can be used with tubs of different widths.

To the inner face of each of the sides a of the tub a bracket F is secured immediately above the rise d⁴ in the bottom, Figs. 3, 5, 35 and 8. In this bracket are the closed and open sockets f and f', adapted to receive the lugs e, carried by the slide E. The open socket f' is provided with a latch f² for closing the same. The latch is pivoted to one end of the 40 arm f³ of the bracket. The purpose of the bracket is to hold the roller mechanism in an operative position or to allow it to be turned into the tub out of the way when not in use. When the roller mechanism is in an operative 45 position, the lugs e of the slide E rest in the sockets of the bracket F. The latch f² is turned to close the open socket f', and thereby holds the lug resting in the said socket in place. When it is desired to turn the roller 50 mechanism into the tub out of the way, the latch f² is turned to open the socket f'. The roller mechanism can then be turned, the lug e, resting in the socket f, forming the pivot, until it rests on the bottom of the tub and 55 entirely contained within the latter, as shown in dotted lines in Fig. 3. The cover C can then be placed in position and a table thereby formed.

To the end pieces d' of the base are secured 60 the standards H by the screws h. Between the lower ends of said standards are mounted the rollers I, that form the bed on which the main roller works. The rollers are three in number, mounted in the arc of a circle. Each 65 of the rollers is made of wood mounted on a metal shaft i', extending through the same, with its ends journaled in bearings i², formed

in the standards H. In the periphery of each of the rollers I are formed the annular grooves i³. The said grooves are cut so as to register 70 when the rollers are in position. Wires i⁴ pass from one side of the base D over the rollers to the other side. Each wire has its ends turned to engage with the inner faces of the sides d of the base. The said wire partly encircles the two outer rollers and rests on the intermediate roller. It is seated in the contiguous grooves of the three rollers. These wires serve to guide the goods through the machine and prevent them from passing between the rollers forming the bed. 75 80

In each of the standards H a groove h' is formed, Figs. 3 and 4, in which is mounted a sliding block h¹², provided with flanges h² and h³, that serve to retain said block in said 85 groove. In the lower-end of the block is formed a bearing h⁴.

The main roller K is considerably larger than those forming the roller-bed. Its shaft k is journaled in the bearings of the blocks 90 h¹². It has its periphery corrugated to enable it to better serve its purpose. These corrugations extend nearly the entire length of the roller, leaving at each end a smooth portion k'. As the roller K rests on the rollers I, if 95 the corrugations extended the entire length of said roller K the machine would make considerable noise by reason of the rollers I slipping into said corrugations. This noise is objectionable, and is avoided in the present instance by providing the larger roller with the smooth sections k'. The said smooth sections bear on the rollers I and prevent the latter from slipping into the corrugations of the roller K. 100 105 110 115

The upper ends of the standards H are connected by the cross-piece L. The latter is made of a hollow casting and is shaped somewhat like two arcs of circles joined together. At each end of the cross-piece is a flange l, through which a screw l' passes and secures the said cross-piece to the upper end of a standard H. Intermediate of the ends of the cross-piece is formed a screw-socket in which the screw l² turns. 115

A spring M bears at each end on the upper end of a sliding block h¹². Intermediate of the ends of said spring a bearing-plate m is mounted, on which the lower end of the screw l² impinges. By means of said spring and said screw the pressure with which the main roller bears upon the roller-bed can be regulated. 120

On the end of the shaft of the main roller a handle of any construction suitable in the premises is mounted for operating the roller 125 mechanism.

Having thus described my invention, what I claim, and desire to secure by Letters Patent, is—

1. In a washing-machine, the combination of 130 a tub, a bracket having an open and a closed socket secured to the inner face of the side of said tub, means for closing said open socket, a base, lugs projecting from said base and regis-

tering with said sockets, standards mounted on said base and having slots, rollers journaled between the lower ends of said standards, spring-pressed blocks movably mounted in said slots, a roller having its shaft journaled in said blocks, and a cross-piece connecting the upper ends of said standards.

5 2. In a washing-machine, the combination of a tub, a bracket having an open and a closed

10 socket secured to the inner face of a side of said tub, means for closing said open socket, a roller mechanism, a lug projecting from said mechanism and pivoted in said closed socket, and a second lug projecting from said mechanism and adapted to register with said open socket.

15 3. In a washing-machine, the combination of a tub, a bracket having a closed and an open socket secured to the inner face of a side of 20 said tub, a latch hinged to said bracket for closing said open socket, a roller mechanism, a lug projecting from said mechanism and pivoted in said closed socket, and a second lug projecting from said mechanism and adapted to 25 register with said open socket.

4. In a washing-machine, the combination of a tub, a bracket having a closed and an open socket secured to the inner face of a side of said tub, means for closing said open socket, a 30 roller mechanism, a slide adjustably mounted on said roller mechanism, a lug projecting from said slide and pivoted in said closed socket, and a second lug projecting from said slide and adapted to register with said open 35 socket.

5. In a washing-machine, the combination of a tub, a bracket having a closed and an open socket secured to the inner face of a side of said tub, a latch hinged to said bracket for 40 closing said open socket, a roller mechanism, a slide adjustably mounted on said roller

mechanism, a lug projecting from said slide and pivoted in said closed socket, and a second lug projecting from said slide and adapted to register with said open socket.

45

6. In a washing-machine, the combination of a tub, a bracket having an open and a closed socket secured to the inner face of the side of said tub, means for closing said open socket, a base, a slide adjustably mounted on said base, 50 lugs projecting from said slide and registering with said sockets, standards mounted on said base and having slots formed therein, rollers journaled between the lower ends of said standards, spring-pressed blocks movably 55 mounted in said slots, a roller having its shaft journaled in said blocks, and a cross-piece connecting the upper ends of said standards.

7. In a washing-machine, the combination of a tub, a bracket having an open and a closed 60 socket secured to the inner face of the side of said tub, a latch for closing said open socket, a base, a slide adjustably mounted on said base, a lug projecting from said slide and pivoted in said closed socket, a second lug projecting 65 from said slide and adapted to register with said open socket, standards mounted on said base and having slots formed therein, rollers journaled between the lower ends of said standards, blocks movably mounted in said 70 slots, a roller having its shaft journaled in said blocks, a cross-piece connecting the upper ends of said standards, a spring resting with its ends on said blocks, and a screw mounted in said cross-piece and impinging on 75 said spring.

In testimony whereof I hereunto affix my signature in the presence of two witnesses.

DAVID I. ECKERSON.
